(57) CLAIM

The ornamental design for a digital disk player, as shown and described.

DESCRIPTION

FIG. 1 is a front view of a digital disk player showing our new design;

FIG. 2 is a rear view thereof;

FIG. 3 is a top plan view thereof;

FIG. 4 is a bottom view thereof;

FIG. 5 is a left side view thereof, the right side view being a mirror image;

FIG. 6 is a left side view thereof with the top cover shown in its open position, the right side view being a mirror image;

FIG. 7 is a top plan view thereof;

FIG. 8 is a front view of a second embodiment of a digital disk player showing our new design;

FIG. 9 is a rear view thereof;

FIG. 10 is a top plan view thereof;

FIG. 11 is a bottom plan view thereof;

FIG. 12 is a left side view thereof, the right side view being a mirror image;

FIG. 13 is a left side view thereof with the top cover shown in its open position, the right side view being a mirror image; and,

FIG. 14 is a top plan view thereof.

The thin diagonal lines in the drawings indicate translucent portions.
